[57] **CLAIM**

The ornamental design for a C.A.T.V. signal splitter, as shown and described.

DESCRIPTION

FIG. 1 is a front elevational view of a signal splitter showing my new design;

FIG. 2 is a right side elevational view thereof;

FIG. 3 is a top view thereof;

FIG. 4 is a left side view thereof;

FIG. 5 is a rear elevational view thereof;

FIG. 6 is a bottom view thereof viewed in the same direction as FIG. 3 rotated 180°;

FIG. 7 is a perspective view of another embodiment all other views being the same as the first embodiment;

FIG. 8 is a front elevational view of a third embodiment thereof;

FIG. 9 is a right side elevational view of a third embodiment thereof;

FIG. 10 is a top view of the third embodiment thereof;

FIG. 11 is a left side elevational view of the third embodiment thereof;

FIG. 12 is a bottom view of the third embodiment thereof;

FIG. 13 is a rear elevational view of the third embodiment of my design.
